UNITED STATES PATENT OFFICE.

JOSEPH M. HOMMEL, OF DETROIT, MICHIGAN.

LEAF-SPRING SPREADER.

1,294,663.

Specification of Letters Patent. Patented Feb. 18, 1919.

Application filed February 26, 1915. Serial No. 10,676.

To all whom it may concern:

Be it known that I, JOSEPH M. HOMMEL, a citizen of the United States, residing at Detroit, county of Wayne, State of Michigan, have invented a certain new and useful Improvement in Leaf-Spring Spreaders, and declare the following to be a full, clear, and exact description of the same, such as will enable others skilled in the art to which it pertains to make and use the same, reference being had to the accompanying drawings, which form a part of this specification.

This invention relates to spreaders for leaf-springs and its object is a simple and inexpensive device for spreading the leaves of vehicle springs in order that a lubricant may be introduced therebetween. A further object of the invention is a device that operates with ease and rapidity and that is adjustable for use with springs of various widths, the arrangement being such that the device may be positively adjusted for use with a spring of any particular width within the capacity of the device. A further object is a device that is strong and serviceable in use and in which the spreader is locked in position when inserted between the leaves preventing a displacement thereof by the tendency of the spring to close up. These and other objects and novel features of construction are hereinafter more fully described and claimed and shown in the accompanying drawings in which—

Figure 1 is a perspective view of a device embodying my invention showing the parts in the position assumed in use.

Fig. 2 is a plan view of the device.

Fig. 3 is a side elevation thereof.

Fig. 4 is a vertical section of the spreader point taken on line $x-x$ of Fig. 3.

Similar characters refer to similar parts throughout the drawing and specification.

The device consists of a shank 1 having an end 2 at right angles thereto terminating in a spreader point 3 formed at right angles to the end 2 and extending toward the rear of the shank parallel therewith. The length of the end portion 2 is such as to allow the device to engage about a spring. The shank and spreader point are preferably formed of a single piece, and one edge of the shank is notched at 4 as shown. A block or carriage 5 of proper form is slidably mounted on the shank, portions 6 of which being adapted to engage the said notches on the shank. The carriage is apertured at 7 to

receive the shank, and a set-screw 8 is provided in the bottom of the carriage adapted to bear against the lower edge of the shank and force the portions 6 into their respective notches which prevents movement of the carriage on the shank. Pivoted to the upper end of the carriage 5 is a lever 10 preferably bifurcated at the pivoted end to receive a roller 11 between the forks thereof. The forked end of the lever is also provided with lugs 12 and 13 on each fork respectively, adapted to engage against the side of the spring when the lever is turned to draw the spreader between the leaves. The notches in the shank are formed one-quarter of an inch from point to point, as vehicle springs usually vary in width by quarter-inches; the first notch nearest the spreader point is so positioned that the carriage may be set for use with a spring of the least width, and by setting the carriage backward away from the spreader point, the device may be set for use with springs of the various standard widths.

In use the spreader point is set to engage between adjacent leaves of a spring, the lever at that time being turned to the position shown by dotted lines in Fig. 2. The lever or prying member is then brought forward forcing the roller 11 into contact with the side of the spring and drawing the spreader point between the leaves as is shown in Fig. 1. When the lever has been brought to final position relatively to the spring as indicated by full lines in Fig. 2, either one or both the lugs 12 and 13 engage against the side of the spring. The lugs are so positioned that on engaging the spring the roller will have passed beyond a center line drawn from the spreader point to the pivot point of the lever in which the tendency of the leaves to close tends to force the roller still farther around. The device is thus locked in position for use.

The roller is formed with a flat face as shown, which has a rolling contact with the side of the spring group and thus little or no friction is produced in forcing the lever to the spreading position. The roller is also greater in length than the thickness of the spreader point and is thus greater in length than the opening between the leaves, whereby the roller is prevented from being forced between the said leaves in operation. It is also to be noted that the spreader point is substantially oval in shape as shown in Fig.

4, and is provided with a circular sharp edge, the purpose of which is to reduce the friction in forcing the spreader between the leaves. The opening between the leaves of 5 a spring when spread is substantially that of a horizontally positioned V. In introducing a flat, wedge-shaped, spreader between the leaves, that side only of the spreader nearer the point of angle of the leaves will 10 be engaged by both the upper and lower leaves while the opposite side of the spreader will be out of engagement therewith or, at least, with one of the leaves, due to the greater distance between the leaves at that 15 point. The wedge-shaped flat point, therefore, is difficult to insert between the leaves, and a cone-shaped point commonly used is also difficult to insert, by reason of the fact that the surface of the leaves contacted by 20 the spreader is a mere line and the force required to insert either a flat or cone-shaped spreader is sufficient to cause either form to cut into and deform the edge of the leaves. With a wedge-shaped oval spreader 25 as herein described and claimed, the shape of the spreader from the center to either side quite closely agrees with the angle between the spread leaves and is thus adapted for use on either side of a spring. Also the 30 surface in contact with the leaves is of such width as not to cut into the same as with the cone-shaped or flat wedge spreader. The oval shaped spreader member is, therefore, more readily inserted and is more efficient 35 in use.

I am aware of other devices for this purpose in which spreader points are inserted between the leaves of a spring by means of a screw which devices are not very serviceable in use, principally for the reason that considerable time and labor is involved in forcing the points between the leaves. With 40 my improved device a spring may be spread in the manner indicated in few seconds, requiring but little effort on the part of the operator. Furthermore the device is very quickly adjustable for use with springs of various widths by simply releasing the set-screw at the bottom of the carriage and raising 45 the carriage to pass over the notches, for which purpose the apertures 7 in the carriage are longer than the width of the shank. The device is also very strong principally by reason of the shank and spreader point being 50 formed of a single piece as described.

Having thus briefly described my invention, its utility, and mode of operation, what I claim and desire to secure by Letters Patent of the United States is—

- 60 1. A leaf-spring spreader comprising a shank, a spreader carried thereby, a pivotally mounted prying member adjustable on the shank and means for locking the prying member in its adjusted position.
- 65 2. A leaf-spring spreader comprising a

shank, a spreader member carried thereby, a carriage adjustable on the shank, means for securing the carriage in its adjusted position, and a prying member consisting of a lever pivoted on the carriage and provided 70 with a flat-faced roller adapted to engage the side of the spring to force the spreader between the leaves, said lever having a part adapted to engage the side of the spring when the point of contact of the roller has 75 passed beyond a line drawn from the spreader point to the pivot point of the lever thereby locking the device in position.

3. A leaf-spring spreader comprising a shank, a spreader member carried thereby, 80 a carriage adjustable on the shank, means for securing the carriage in its adjusted position, a lever pivoted to the carriage, a roller mounted in the short end of the lever, said roller having a flat face for rolling contact 85 with the side of the spring and having a length greater than the thickness of the spreader.

4. A leaf-spring spreader comprising a shank, a spreader member formed integrally 90 therewith, a prying member adjustable on the shank, and means for securing the prying member in its adjusted position, said prying member including a pivoted lever having a flat-faced roller secured in the short end 95 for engaging the side of the spring.

5. A leaf-spring spreader comprising a shank of L shaped form, a spreader point formed integrally therewith at the end of the short arm and lying parallel with the 100 body of the shank, said body of the shank being notched at regular intervals, a block apertured to receive the shank body and adapted to engage in said notches, means for locking the block in any of the notches whereby the device is positively adjustable 105 for use with springs of various standard widths, a lever pivoted to the block practically in alinement with the spreader point, a roller carried at the short end of the lever 110 having a flat face for engaging the side of the spring providing a pry for forcing the spreader point between the leaves, the length of the roller being greater than the thickness of the spreader point, and a spring engaging portion on the lever limiting the prying movement of the lever substantially as and 115 for the purpose described.

6. In a leaf-spring spreader, a spreader member having a sharp edge substantially 120 semi-circular in contour, means whereby the spreader member may be forced between the leaves, and a flat-faced roller riding against the side of the spring opposite to that engaged by the spreader.

7. In a leaf-spring spreader, a shank, a spreader point supported thereby having a sharp edge substantially semi-circular in contour for engaging between the leaves on one side of the spring, and a flat-faced roller 130

member having rolling contact with the opposite side of the spring in opposition to the spreader.

8. In a leaf-spring spreader, a shank, a spreader point formed integrally therewith, said shank being notched, a block slidable on the shank adapted to engage in the said notches, means for securing the block in adjusted position, a lever pivoted to the block, 10 a roller carried in the short arm of the lever adapted for engagement with the side of the spring to force the spreader between the leaves, and lugs on the lever adapted to engage the side of the leaves when the roller 15 is turned slightly beyond a line drawn from the spreader point to the pivot point of the lever.

9. In a leaf-spring spreader, a substantially L shaped shank having a spreader 20 point formed at the end of the short arm parallel with the body of the shank, a block adjustable on the body of the shank, a lever pivoted on the block, a roller carried in the short arm of the lever having a flat face 25 adapted to contact the side of the spring to force the spreader point between the leaves, and means on the lever adapted to engage the side of the spring upon movement of the roller beyond a line drawn from the spreader 30 point to the pivot point of the lever whereby the spreader is locked in position.

10. In a leaf spring spreader, a wedge shaped spreader member oval in cross-section having a sharp edge substantially semi-circular in contour, a pivoted lever, and a 35 roller carried by the lever adapted to engage the side of the spring when the lever is operated to force the spreader between the leaves.

11. In a leaf spring spreader, a shank, a spreader member carried thereby, a carriage 40 adjustable on the shank, a lever pivoted to the carriage, and a roller carried by the lever adapted to have a rolling contact with the side of the spring when the lever is 45 turned to force the spreader between the leaves.

12. In a leaf-spring spreader, a spreader member substantially oval in cross section 50 having a sharp edge practically semi-circular in contour, a pivoted lever for forcing the spreader between the leaves on one side of the spring, and a flat-faced roller riding against the other side of the spring in opposition to the spreader member. 55

In testimony whereof, I sign this specification in the presence of two witnesses.

JOSEPH M. HOMMEL.
